UNITED STATES PATENT OFFICE.

HARRY SHOEMAKER, OF PHILADELPHIA, PENNSYLVANIA, ASSIGNOR TO MARIE V. GEHRING AND THE CONSOLIDATED WIRELESS TELEGRAPH AND TELEPHONE COMPANY, OF PHILADELPHIA, PENNSYLVANIA.

SYNCHRONIZER.

SPECIFICATION forming part of Letters Patent No. 717,768, dated January 6, 1903.

Application filed April 25, 1902. Serial No. 104,614. (No model.)

To all whom it may concern:

Be it known that I, HARRY SHOEMAKER, a citizen of the United States, residing at Philadelphia, in the county of Philadelphia and State of Pennsylvania, have invented a new and useful Synchronizer, of which the following is a specification.

My invention comprises means whereby a plurality of messages may be simultaneously transmitted and received by a single apparatus without confusion or interference between the several messages.

It comprises commutating devices whereby the transmitters are brought alternately into action with such rapidity that each transmitter is independent of and does not interfere with the others.

It comprises also commutating devices whereby the receiving-circuits are brought alternately into action with such rapidity that each receiver is independent of and does not interfere with the others and properly selects out the impulses intended for it.

It comprises, further, means whereby the synchronous movement of the apparatus of the several stations of a system is obtained for use in instruments where the energy representing the messages is transmitted over artificial conductors or through the natural media in the electroradiant form.

I have shown the synchronizing apparatus comprising my invention as applied to a system employing electroradiant energy, such as a wireless signaling system, in which there are involved circuit arrangements which comprise a part of my invention.

My invention comprises, further, means for driving the commutators, for throwing them into and out of action, so that they will start and operate in the proper angular relations, and means for controlling very accurately the speed of the driving-motor.

It comprises many other details of construction and arrangements of parts, which are pointed out in the following description and appended claims.

Reference is to be had to the accompanying drawings, in which—

Figure 1 is a side view, partly in section and

partly in elevation, of the synchronizing apparatus and commutators controlled thereby. Fig. 2 is a side view of a portion of the apparatus shown in Fig. 1, such view being taken from the opposite direction from that of Fig. 1. Fig. 3 is an end view of a portion of the apparatus shown in Fig. 2 along with adjusting means. Fig. 4 is a view of one of the commutator-cylinders. Fig. 5 is a plan view of a speed-controlling means for the driving-motor shown in Fig. 1 in side elevation. Fig. 6 is an end view of one of the magnetic clutch members, showing radial corrugations. Fig. 7 is a diagrammatic view of the circuits employed in the control of the driving-motor to attain uniform speed. Fig. 8 is a diagrammatic view of the magnets and the controlling-circuit for clutching the commutator-shaft to the power-shaft and for unlocking and permitting the rotation of the commutator-shaft. Fig. 9 is a diagrammatic view of the circuits at a station, showing both the transmitting and receiving circuits in their relation to the synchronously-driven commutators. Fig. 10 is a side elevation showing a modified means for clutching the power-shaft to the commutator-shaft. Fig. 11 is an end view of the modification shown in Fig. 10. Fig. 12 is a top plan view of the same modification. Fig. 13 is a detail showing the magnets and armature of the modified clutch. Fig. 14 is a detail showing the armature and the member attached to or integral therewith which acts directly upon the clutch member. Fig. 15 shows a face view of one of the clutch members.

In Fig. 1, 1 is a metallic box, upon the inside of which is a plate 2, supporting the apparatus, and upon the outside of which is the platform, 3, of insulating material, which is secured to and supported from the box 1 by brackets 4 and 5. The metal box 1 is used to shield the receiving apparatus from any effects of sparks or waves generated at the transmitting-commutator or at the contacts of any circuits which are ruptured from time to time.

6 is the armature of a shunt-wound motor, such as is used for driving phonographic record-cylinders. This armature is of the slotted

Gramme-ring type, about nine or ten inches in diameter, and of considerable mass, and therefore considerable moment of inertia. It is mounted upon the vertical shaft 7, bearing 5 by conical pivots in the cups 8 and 9, cup 8 being secured to the bottom of box 1 on a block of insulation 10. Upper bearing-cup 9 is in the end of a vertical member 11, which is supported in the bracket 12. At 13 is shown a belt-wheel, from which is driven by means of a small ribbon or belt a centrifugal governor which controls the circuit of the armature only of the motor, the field-magnets remaining at all times energized. Upon an 15 increase of speed the centrifugal governor short-circuits the armature, and inasmuch as the field remains energized it is promptly damped, and upon reduction of speed the centrifugal governor permits the opening of 20 the armature-circuit. This centrifugal governor is well known in connection with phonographic motors and requires no further description herein. Upon the same shaft 7 is secured an annular iron body 14, having a 25 plurality of lugs or projections 15, as shown in Fig. 5. Disposed around the iron mass 14 are the electromagnets 16, 17, 18, and 19, spaced equally and similarly to the lugs 15 upon the body 14.

30 At 20 is shown a beveled gear, also securely mounted upon the shaft 7. 20 meshes with a complementary gear 21, which is rigid with a shaft having its bearings in the sleeve 22 at the top of standard 23. This shaft carries 35 at its other extremity an iron radially-corrugated disk 24. The corrugations are shown in Fig. 6. Stationary upon the sleeve 22 and in close arrangement with the plate 24 is the magnet-coil 25, in whose magnetic circuit is 40 the iron plate 26, which is similarly corrugated. 26 is, however, on the independent commutator-shaft 27, which has its bearings in the sleeve 28, supported on standard 29 30, and sleeve 31, supported upon the standard 45 32. The bearing 30, as shown, is insulated from the end of box 1 by the member 33.

50 Coil 25 and plates 24 and 26 form a magnetic clutch, of which the member 24 is constantly rotating, being driven by armature 6, and at predetermined times coil 25 is energized, which then causes the engagement of 55 24 and 26, resulting in the transmission of power from armature 6 to shaft 27 and causing the shaft 27 to rotate at the same speed as the plate 24.

Upon the shaft 27 are secured the commutator-cylinders 34, 35, and 36, each comprising, as shown in Fig. 4, a mass of insulating material 37, which supports segments 38 and 60 39, of conducting material, which are on opposite sides of the cylinder 37, each of which embraces an arc of ninety degrees. These segments are in electrical connection with a continuous ring-conductor concentric with the shaft 27 and upon which bears a brush.

65 40, 41, and 42 are standards, on the top of which are the insulating members 43, 44, and

45, respectively, which carry the brush-holders 46, 47, and 48, respectively. The other brush-holders are partially hidden.

Upon the shaft 27 are threads 49, which are engaged by a pin 50 upon the end of a lever 51, which is fastened to a barrel 52, capable of longitudinal motion upon the rod 53. In practice the threads 49 are of much smaller pitch than shown in the drawings and occupy a somewhat greater length on the shaft 27. The motion of the barrel 52 toward the left in Fig. 1 or toward the right, as shown in Fig. 2, is resisted by the coil-spring 54, surrounding said rod 53. Projecting downwardly from the barrel 52 is the lever 55, which extends into the path of movement of the frame 56, which is mounted upon the rock-shaft 57. The spiral spring 58 (shown in Fig. 3) is adjusted by means of screw 59, extending through the side of the box 1, and tends to rotate the lever 51 in a counter-clockwise direction as viewed in Fig. 3, so as to normally keep the pin 50 in engagement with the threads 49. The rock-shaft 57 has a bearing in standard 29 and also in the member 60 and passes through the end of box 1 through an insulated joint 61. Outside of the box and mounted upon said rock-shaft 57 is the armature 62 of the magnets 63, whose back armature and support is shown at 64, Fig. 2. Upon the energization of the magnets 63 the armature 62 is attracted, which causes a rotation of shaft 57 in such a direction as to cause the frame 56 as viewed in Fig. 3 to rotate in a counter-clockwise direction and operate the lever 55, barrel 52, and lever 51 in opposition to spring 58 in such a direction as to remove the pin 50 from engagement with the threads 49. Upon the de-energization of magnets 63 spring 58 causes pin 50 to reengage the threads 49 and the armature 62 to recede from the magnets 63.

During the rotation of the shaft 27 and the engagement of pin 50 with threads 49 barrel 52, in virtue of this engagement between pin 50 and threads 49, moves toward the left, as shown in Fig. 1, compressing the spring 54 and after a certain travel causes pin 65 to press leaf-spring 66 to the left and break circuit at the contact 67. Said contact 67 is supported upon standard 29 and insulated therefrom. The leaf-spring 66 is also supported upon and insulated from the standard 29.

The number of threads 49 on shaft 27 is such that the time consumed by the pin 50 in traversing them is somewhat in excess of the interval of time between words or sentences in the transmission.

At 68 is shown an electromagnet whose armature 69 is pivoted at its center to the standard 29 and whose upper end extends into the path of the pin 70, secured to the disk 26 at or near its circumference. The armature 69 is normally held in the position shown in Fig. 1 in the path of the pin 70 by means of the spiral spring 71, which is adjusted by

thumb-screw 72, fitted in standard 23. Upon the energization of the magnets 68 the armature 69 is attracted in opposition to the spring 71 and the upper end of the armature 69 is 5 removed from the path of the pin 70.

In Fig. 7 is shown pendulum 73, which may be kept constantly swinging by well-known electromechanical means and whose bob 74 carries at its lower extremity a contact-piece 10 75, which is adapted during the vibrations of the pendulum to connect successively for brief intervals of time with the contacts 76, 77, and 78, all of which are connected together and in circuit with source of energy 79, the magnets of the relay 80, the conductor 81, and the pendulum 73. At each contact the relay 80 is energized and its tongue 82 makes contact with 83 and closes circuit therewith for a brief instant, thereby energizing magnets 16, 15 20 17, 18, and 19 from the source of energy 84. The length of the pendulum 73 is so chosen and the number of lugs 15 upon the member 14 and their associated magnets so chosen with regard to the speed of the armature 6 of the motor that at each contact at 76, 77, and 25 78 the lugs 15 will be exactly opposite the poles of the magnets if the armature 6 is rotating at the proper speed. Should said armature lag slightly, the lugs 15 would be 30 slightly displaced from the point of symmetry with the poles of the magnets 16, 17, 18, and 19, and upon the energization of these magnets they would give an accelerating impulse to the disk 14, which in turn would 35 bring the armature of the motor to the precise angular position it ought to occupy had it not departed from absolutely uniform speed. In case the armature 6 should travel too rapidly the lugs 15 would be in advance 40 of the poles of the magnets at certain instants, and the energization of said magnets would cause a retarding impulse to be applied to disk 14 and armature 6. These magnets are energized so frequently that the armature 45 6 could at most be out of its proper angular position by a few degrees only. The device described in connection with Fig. 7 operates in connection with the centrifugal device described above, the latter operating upon relatively great changes of speed, whereas the 50 pendulum-control (shown in Fig. 7) maintains the disk 14, and therefore the disk 24 and shaft 27, in practically absolutely uniform rotation.

55 Fig. 8 shows the arrangement of circuits of the magnets 25 and 68 in connection with their circuit-controller 66 67. 85 is a source of energy for energizing the magnets just named, and, as previously stated, when the 60 pin 65 has been moved sufficiently far to the left, as shown in Fig. 1, the spring 66 breaks the circuit at 67. The result is that the clutch 24 26 loses its magnetism, and therefore its ability to transmit power. A spring 71 retracts armature 69, so as to come into the path of the pin 70 and stop the shaft 27 in a certain angular position.

In Fig. 9 is shown the arrangement of the circuits at the transmitter and receiver. 86 is an operator's key which closes a circuit through 70 the contacts 87, and while being depressed for this purpose a lug on the lower side of the key brings into contact the points 88 at the same moment the points 87 engage each other. Two circuits are therefore closed. The one controlled by contacts 87 extends through conductor 89, brush 90, segment 38 of the commutator, brush 91, source of energy 92, primary of the coil 93, and conductor 94. This results in the emission of waves from the radiating aerial conductor 102, connected to one side of the spark-gap 103, the other side of which connects to earth-plate 104. The other circuit includes the contacts 88, the source of energy 100, and one winding of the electromagnet 63. The result is that as the operator depresses key 86 to send the first impulse magnet 63 is energized, which then causes pin 50 to be disengaged from the threads 49. So long as messages are being sent 63 is energized and the pin 50 is prevented from engagement with the threads 49. A second key 95 controls contacts 96 and 97 in the same manner as described in connection with key 86, contacts 96 controlling the circuit through 95 brush 99, brush 91, source of energy 92, primary of the coil 93, and the conductor 94. The contacts 97 control a circuit embracing the source of energy 101 and the remaining winding upon the magnet 63. The brushes 100 90 and 99 are arranged at an angle of ninety degrees with each other, so that at the instant one brush comes in engagement with the commutator the other brush has just left contact with the other segment. The result is that 105 as the commutator rotates rapidly key 86 controls transmitter-coil 93 for one half of the time and the key 95 controls it for the remaining half of the time and alternately in rapid succession. The speed of the commutator is such that to all intents and purposes either key sends its dots and dashes without any interruption whatever. In other words, the commutator rotates so rapidly that the time required to make a dot is sufficiently 110 long for the commutator to make several revolutions, and therefore in reality break up said dot into several component dots. Upon ceasing to send messages from either key 86 or 95 the apparatus shown in Fig. 1 continues 115 to revolve, and 63 being deenergized point 50 engages with the threads 49 and causes the barrel 52 to move to the left, as shown in Fig. 1, until 65 opens a circuit of the coils 25 and 68, which then causes the stoppage of the 120 shaft 27. Upon the first closure of the circuit at either key, however, 63 is energized, the pin 50 is retracted from engagement with the threads 49, and the barrel 52 is forced to the right along its guide-rod 57, as shown in 125 Fig. 1, permitting the closure of the circuit at 66 and 67, resulting in an energization of magnets 25 and 68, which results instantly in the 130 rotation of the shaft 27 and its commutators

at full speed. The inertia of the power-shaft and the members rotating therewith is so great compared with the shaft 27 and the light commutators carried thereby that such practically instantaneous acquisition of speed is possible.

The receiver which is shown in Fig. 9 in conjunction with the transmitter may use the same aerial conductor 102 as shown in connection with the transmitter. The circuit connections from the aerial conductor 102 extend through brush 105 to the contact-ring of the commutator 35, upon whose two segments bear the brushes 106 and 107, arranged at right angles to each other. From brush 106 extends a conductor, which embraces the wave-responsive device, here shown as a Branly tube 108, whose other terminal connects through brush 109, through the commutator 36, to brush 110, to earth-plate 104. In shunt to the tube 108 is a circuit including relay 111 and source of energy 112. The tongue 113 in this relay includes and controls the same circuit controlled by contacts 97 of the key 95—namely, the source of energy 101 and one winding of the magnet 63. Brush 107 communicates with a second tube 114, in shunt to which is a circuit including the relay 115 and source of energy 116. The tongue 117 of said relay controls a circuit embracing a source of energy 100 of the magnet 63, which is the same circuit as controlled by contacts 88 of the key 86. The other terminal of the tube 114 connects through brush 118, through commutator 36, brush 110 to earth-plate 104. The brushes 109 and 118 are at right angles to each other, similar to brushes 106 and 107. At the first arriving impulse either tube 108 or 114 causes the actuation of either relay 111 or 115, which results in the energization of one or the other of the coils of magnet 63. The receiving mechanism being at rest, the circuit of the receiver at 66 and 67 is opened and the barrel 52 at its extreme left position, with the pin 50 in engagement with the threads 49. The energization of magnets 63 due to the first impulse just arriving, as just described, then instantly withdraws the pin 50 from engagement with the threads 49, spring 54 repels the barrel 52 to the right, permitting the closure of the circuit at 66 and 67, which results in the energization of magnets 25 and 68. This, as previously described, causes the shaft 27 and its associated commutators to instantly come up to speed and to start from an angular position such that the commutators of the receiving device will rotate synchronously with those of the transmitting device. The speeds of the armatures in both instruments are very closely the same, and if not precisely the same are absolutely regulated to uniform speed by the pendula 73, which vibrate at the same rate at both stations. When key 86, for example, at the transmitting-station is depressed, it sends the first impulse to the magnet 63 of the transmitter and also the first impulse to

the receiving-station, which energizes, by means of the relay, as just described, the magnet 63 of the receiver, and in consequence the two shafts 27, one at the transmitter and one at the receiver, start off together and from the same angular position, which is determined by the pins 70, projecting from the disk 26 of each instrument.

Considering the transmitting portion of Fig. 9 as being at one station and the receiver portion at another, it is seen that as either key 86 or 95 is depressed the transmitting apparatus starts, as does also the receiving apparatus, which then rotates in synchronism with the transmitting apparatus. When brush 90, for example, is just in contact with segment 38 of the commutator 34, the brush 107 of the receiver is likewise just coming into contact with corresponding segment of its commutator 35. The impulses then which are controlled by the key 86 are selected out to the Branly tube 114. In the same manner key 95 in conjunction with brush 99 controls impulses which are selected out by brush 106 and the tube 108. It is thus seen that with the apparatus herein shown and described two messages may be simultaneously sent and received without interference with each other, using the same transmitting source of power and the same receiving aerial conductor. It is seen also that by the additional commutator 36 in the receiver the tubes 108 and 114 are entirely cut out of circuit when the brushes pass on to the insulating-segments. It is possible to join the left-hand terminals of the tubes 108 and 114 to ground-plate 104 directly; but it is preferable to cause the complete isolation of the tubes, as just described, due to the commutator 36.

It is to be understood that relays 111 and 115 in addition to controlling the windings of the magnets 63 control the usual recording devices, tappers, &c.

In Figs. 10 to 15, inclusive, I have shown a modified and preferred form of electromagnetic means for coupling the power-shaft and the shaft 27 together. The coil 25 is still shown as present, though it may be omitted. The magnets 119 are in the same circuit with coils 25 and 68 or replace 25 entirely. The armature 120 of said magnet is pivoted at 121 on the standard 29 and carries two vertical arms 122, carrying at their upper ends small antifriction-rollers 123. Upon the energization of magnets 119 the armature 120 is attracted downwardly, which causes then the rollers 123 to press to the left, as shown in Fig. 10, against corrugated plate 26' to engage with a similar plate 24', thereby securing mechanical connection between the power-shaft and the driven-shaft 27. This then in the absence of the coil 25 is a purely mechanical connection between plates 24' and 26' and not dependent upon electromagnetism for the attraction between the two plates.

Though I have shown apparatus constructed to send and receive simultaneously

two messages, it is to be understood within the scope of my invention to enlarge the system, so as to make it possible to send still more messages without interference with each other. It is also to be understood that this apparatus is adaptable for use on multiplex telegraph systems where the energy is transmitted over line-wires.

I do not wish to be limited to the precise arrangement of apparatus or circuits, inasmuch as many variations may be made therein without departure from the spirit or scope of my invention.

What I claim is—

- 15 1. In a synchronizer for use in a wireless-telegraph system, a rotating power-shaft, a shaft carrying circuit-changing means, means for coupling the said shafts together, and means responsive to electromagnetic waves 20 for actuating said coupling means.
- 20 2. In a synchronizer for use in a wireless-telegraph system, a rotating power-shaft, a shaft carrying circuit-changing means, a member upon the end of each shaft, means 25 for causing the engagement of said members and an electromagnetic wave-responsive device for actuating said last-mentioned means.
- 25 3. In a synchronizer for use in a wireless-telegraph system, a rotating power-shaft, a shaft carrying circuit-changing means, magnetic means for coupling the said shafts together, and means responsive to electromagnetic waves for actuating said coupling means.
- 30 35 4. In a synchronizer for use in a wireless-telegraph system, a rotating power-shaft, a shaft carrying circuit-changing means, electroresponsive means for coupling the said shafts together and means responsive to electromagnetic waves for actuating said coupling means.
- 40 45 5. In a synchronizer for use in a wireless-telegraph system, a rotating power-shaft, a shaft carrying circuit-changing means, means for coupling the said shafts together, means for causing the disengagement of said shafts and means responsive to electromagnetic waves for actuating said coupling and disengaging means.
- 50 55 6. In a synchronizer, a power-shaft, a shaft carrying commutating means, electric means for coupling said shafts, electrically-operated means for causing the disengagement of said shafts and a common circuit for energizing the coupling and disengaging means.
- 60 7. In a synchronizer, a power-shaft, a shaft carrying commutating means, electrical means for coupling said shafts, and electrically-operated mechanical means for causing the disengagement of said shafts.
- 65 8. In a synchronizer, a power-shaft, a shaft carrying commutating means, electrical means for coupling said shafts, and electrically-operated mechanical means for causing the disengagement of said shafts upon a release of the coupling means.
9. In a synchronizer, a power-shaft, a shaft

carrying commutating means, a magnetic coupler, and a stop in a definite angular position with respect to the commutating means, whereby the shafts are disengaged upon release of the coupler.

10. In a synchronizer, a power-shaft, a shaft carrying commutating means, a magnetic coupler for said shafts, a stop in a definite angular position with respect to the commutating means, and means extending into the path of said stop, whereby the shaft carrying the commutating means starts from and comes to rest at a definite position.

11. In a synchronizer, a power-shaft, a shaft carrying commutating means, a coupler for said shafts, a stop on the shaft carrying the commutating means, and electrically-controlled means extending into the path of said stop.

12. In a synchronizer, a power-shaft, a shaft carrying commutating means, a coupler for said shafts, a stop on the shaft carrying the commutating means, means extending into the path of said stop, an electromagnet controlling said means and a time circuit-controller in the circuit of said electromagnet.

13. In a synchronizer, a power-shaft, a shaft carrying commutating means, a coupler for said shafts, a stop on the shaft carrying the commutating means, means extending into the path of said stop, an electromagnet controlling said means, and a time circuit-controller in the circuit of said electromagnet and controlled by the shaft carrying the commutating means.

14. In a synchronizer, a power-shaft, a shaft carrying commutating means, a coupler for said shafts, a stop on the shaft carrying the commutating means, means for engaging said stop, an electromagnet controlling said means, and means operated by the shaft carrying the commutating means for controlling the circuit of said electromagnet after certain conditions have obtained for a definite time interval.

15. In a synchronizer, a power-shaft, a shaft carrying the commutating means, a coupler for said shafts, a stop on the shaft carrying the commutating means, a lever extending into the path of said stop, a spring applied to said lever, an electromagnet operating upon said lever, and means operated by the shaft carrying the commutating means for controlling the circuit of said electromagnet, after certain conditions have obtained for a definite time interval.

16. A power-shaft, a shaft carrying commutating means, a coupler for said shafts, a stop on the shaft carrying the commutating means, means extending into the path of said stop, an electromagnet controlling said means, a circuit-controller in the circuit of said electromagnet, and means engaging the shaft carrying the commutating means, for operating said circuit-controller.

17. A power-shaft, a shaft carrying commutating means, an electromagnet controlling

- means for coupling said shafts, a stop on the shaft carrying the commutating means, means extending into the path of said stop, an electromagnet controlling said means and a circuit-controller in the circuit of said electromagnets operated after a definite time interval by the shaft carrying the commutating means.
18. A power-shaft, a driven shaft carrying commutating means, means for coupling said shafts, an electromagnet controlling said means, a stop on the driven shaft, an electromagnet-controlling means extending into the path of said stop, a circuit-controller in the circuit of said electromagnets, and means engaging the driven shaft for operating said circuit-controller.
19. A power-shaft, a driven shaft carrying commutating means, a disk on an end of each shaft, means for causing the engagement of said disks, a stop on the disk of the driven shaft, means extending into the path of said stop, an electromagnet controlling said means, and a circuit-controller in the circuit of said electromagnet and operated by the driven shaft.
20. A power-shaft, a driven shaft, a disk on an end of each shaft, an electromagnet for causing the engagement of said disks, a stop on the disk of the driven shaft, means extending into the path of said stop, an electromagnet controlling said means, and a circuit-controller in the circuit of said electromagnets operated by the driven shaft.
21. A power-shaft, a driven shaft, a disk on an end of each shaft, an electromagnet for causing the engagement of said disks, a stop on the disk of the driven shaft, means extending into the path of said stop, an electromagnet controlling said means, and a circuit-controller in the circuit of said electromagnets operated by the driven shaft after a definite time interval.
22. A power-shaft, a magnetic mass secured thereto, a driven shaft carrying commutating means, a coupler for said shafts, electromagnets operating upon said magnetic mass, a pendulum, and a circuit including said electromagnets controlled thereby.
23. A power-shaft, a magnetic mass secured thereto, a driven shaft carrying commutating means, a stop on the driven shaft, electrically-controlled means extending into the path of said stop, electromagnets operating upon said magnetic mass, a pendulum, and a circuit including said electromagnets controlled by said pendulum.
24. A power-shaft, a magnetic mass secured thereto, a driven shaft, a coupler for said shafts, a stop on the driven shaft, means extending into the path of said stop, an electromagnet controlling said means, a circuit-controller in the circuit of said electromagnet operated by the driven shaft, a pendulum, a circuit including electromagnets controlled thereby, said electromagnets operating upon the magnetic mass to regulate the speed thereof.
25. A power-shaft, a magnetic mass secured thereto, a driven shaft, an electromagnet for coupling said shafts, a circuit-controller included in the circuit of said electromagnet and operated by the driven shaft, a pendulum, a circuit including electromagnets controlled thereby, said electromagnets operating upon said magnetic mass to regulate the speed thereof.
26. A power-shaft, a magnetic mass secured thereto, a driven shaft, a coupler for said shafts, a stop on the driven shaft, means extending into the path of said stop, an electromagnet controlling said means, a circuit-controller included in the circuit of said electromagnet and operated by the driven shaft, a pendulum, a circuit including electromagnets controlled thereby, said electromagnets operating upon said magnetic mass to regulate the speed thereof.
27. In a synchronizer adapted for use in a wireless-telegraph system, a power-shaft, a driven shaft, and means responsive to the first transmitted or received impulse for actuating means for coupling the said shafts together.
28. In a synchronizer adapted for use in a wireless-telegraph system, a power-shaft constantly rotating, a driven shaft normally at rest and means responsive to the first transmitted or received impulse for actuating means for coupling said shafts together.
29. In a synchronizer adapted for use in a wireless-telegraph system, a power-shaft, a driven shaft and means responsive to the first transmitted or received impulse for energizing means whereby a magnetic coupler may be actuated.
30. In a synchronizer, a power-shaft, a driven shaft, a stop on the driven shaft, a member projecting into the path of said stop, and electric means responsive to the first received and transmitted impulse for withdrawing said member from the path of said stop.
31. In a synchronizer, a power-shaft, a driven shaft, a lock holding said driven shaft in a definite angular position, and electric means responsive to the first transmitted or received impulse for unlocking the driven shaft.
32. In a synchronizer, a power-shaft, a driven shaft, a coupler for said shafts, a lock holding said driven shaft in a definite angular position, and electric means responsive to the first transmitted or received impulse for unlocking the driven shaft and coupling it to the power-shaft.
33. In a synchronizer, a power-shaft, a driven shaft, a coupling-magnet, a magnet controlling a member extending into the path of a stop on the driven shaft, and electric means responsive to the first received or transmitted impulse for controlling the circuit including the windings of said magnets.

34. In a synchronizer, a power-shaft, a driven shaft, a coupling-magnet, a magnet controlling a member extending into the path of a stop on the driven shaft, and electric means responsive to the first received or transmitted impulse for energizing said magnets.
35. In a synchronizer, a power-shaft, a driven shaft, a coupler for said shafts, a lock holding said driven shaft in a definite angular position, and electric means responsive to the first transmitted or received impulse for controlling the circuit of the coupler-magnet and the means for unlocking the driven shaft.
36. In a synchronizer, a shaft, threads thereon engaged by a lever, a barrel supporting said lever pivoted and sliding upon a guide-rod, a spring opposing the motion of said barrel, and circuit-contacts controlled by said lever.
37. In a wireless-telegraph system, a uniformly-rotating power-shaft at each station, a driven shaft at each station carrying transmitting and receiving commutators in definite angular position, and an electromagnetic wave-responsive device at each station responsive to the first transmitted or received impulse for coupling the driven to the power shaft.
38. In a wireless-telegraph system, a power and driven shaft at each station, transmitting and receiving commutators on each driven shaft, means for holding all the commutators at rest in a definite angular position, and an electromagnetic wave-responsive device responsive to the first transmitted or received impulse for coupling the driven to the power shaft.
39. In a wireless-telegraph system, a power and driven shaft at each station, transmitting and receiving commutators on each driven shaft, means holding all the commutators at rest in a definite angular position, an electromagnetic wave-responsive device responsive to the first transmitted or received impulse for coupling the driven to the power shafts, and means for uncoupling the shafts a definite interval of time after the last impulse transmitted or received.
40. In a wireless-telegraph system, a uniformly-rotating power-shaft at each station, a driven shaft at each station carrying commutators in definite angular position, and an electromagnetic wave-responsive device at each station responsive to the first transmitted or received impulse for coupling the driven to the power shaft.
41. In a wireless-telegraph system, a power and driven shaft at each station, commutators on each driven shaft, means for holding all the commutators at rest in a definite angular position, and an electromagnetic wave-responsive device responsive to the first transmitted or received impulse for coupling the driven to the power shaft.
42. In a wireless-telegraph system, a power and driven shaft at each station, commutators
- on each driven shaft, means holding all the commutators at rest in a definite angular position, an electromagnetic wave-responsive device responsive to the first transmitted or received impulse for coupling the driven to the power shaft, and means for uncoupling the shafts a definite interval of time after the last impulse transmitted or received.
43. In a wireless-telegraph system, a power-shaft at each station rotating uniformly and at the same speed, a driven shaft for each power-shaft carrying a commutator, and an electromagnetic wave-responsive device at each station responsive to the first transmitted or received impulse for coupling the driven to the power shaft.
44. In a wireless-telegraph system, a power-shaft at each station rotating uniformly and at the same speed, a driven shaft for each power-shaft carrying a commutator, means for holding the commutators at rest in a definite angular position and an electromagnetic wave-responsive device responsive to the first received or transmitted impulse for coupling the driven to the power shafts.
45. In a wireless-telegraph system, a power-shaft at each station rotating uniformly and at the same speed, a driven shaft for each power-shaft carrying a commutator, an electromagnetic wave-responsive device responsive to the first transmitted or received impulse for coupling the driven to the power-shafts, and means for uncoupling the shafts a definite interval of time after the last transmitted or received impulse.
46. In a wireless-telegraph system, a power-shaft at each station rotating uniformly and at the same speed, a driven shaft for each power-shaft carrying a commutator, means for holding the commutators at rest in a definite angular position, an electromagnetic wave-responsive device responsive to the first transmitted or received impulse for coupling the shafts, and means for uncoupling the shafts a definite interval of time after the last transmitted or received impulse.
47. In a wireless-telegraph system, a power-shaft at each station rotating uniformly at a definite rate, a driven shaft for each power-shaft carrying a commutator, means for locking the commutators at rest in a definite angular position, an electromagnetic wave-responsive device responsive to the first transmitted or received impulse for unlocking the commutators and coupling the driven to the power shafts, and means for uncoupling the shafts a definite interval of time after the last impulse.
48. In a wireless-telegraph system, a power-shaft at each station rotating uniformly and at the same speed, a driven shaft for each power-shaft carrying a transmitting and receiving commutator, and an electromagnetic wave-responsive device at each station responsive to the first transmitted or received impulse for coupling the driven to the power shaft.

49. In a wireless-telegraph system, a power-shaft at each station, rotating uniformly and at the same speed, a driven shaft for each power-shaft carrying a transmitting and receiving commutator, means for holding the commutators at rest in a definite angular position and an electromagnetic wave-responsive device responsive to the first received or transmitted impulse for coupling the driven-shaft to the power shafts.
50. In a wireless-telegraph system, a power-shaft at each station rotating uniformly and at the same speed, a driven shaft for each power-shaft carrying a transmitting and receiving commutator, an electromagnetic wave-responsive device responsive to the first transmitted or received impulse for coupling the driven-shaft to the power shafts, and means for uncoupling the shafts a definite interval of time after the last transmitted or received impulse.
51. In a wireless-telegraph system, a power-shaft at each station rotating uniformly and at the same speed, a driven shaft for each power-shaft carrying a transmitting and receiving commutator, means for holding the commutators at rest in a definite angular position, an electromagnetic wave-responsive device responsive to the first transmitted or received impulse for coupling the shafts, and means for uncoupling the shafts a definite interval of time after the last transmitted or received impulse.
52. In a wireless-telegraph system, a power-shaft at each station rotating uniformly at a definite rate, a driven shaft for each power-shaft carrying a transmitting and receiving commutator, means for locking the commutators at rest in a definite angular position, an electromagnetic wave-responsive device responsive to the first transmitted or received impulse for unlocking the commutators and coupling the driven to the power shafts, and means for uncoupling the shafts a definite interval of time after the last impulse.
53. In a wireless-telegraph system comprising synchronously-operating mechanism at each station, a key controlling the transmitter-circuit and also controlling the operation of the synchronously-operating mechanism.
54. In a wireless-telegraph system comprising synchronously-operating mechanism at each station, a key controlling the transmitter-circuit and also controlling simultaneously the operation of the synchronously-operating mechanism.
55. In a wireless-telegraph system comprising synchronously-operating mechanism at each station, a key controlling the transmitter-circuit and also controlling the starting of the synchronously-operating mechanism.
56. In a wireless-telegraph system comprising synchronously-operating mechanism at each station, a key controlling the transmitter-circuit and also controlling a circuit including means which control the locking of the synchronously-operating mechanism.

57. In a wireless-telegraph system comprising synchronously-operating mechanism at each station, a key controlling the transmitter-circuit and also controlling a circuit including means which control the starting and locking of the synchronously-operating mechanism. 70
58. In a wireless-telegraph system comprising synchronously-operating mechanism at each station, a key controlling the transmitter-circuit and also controlling a circuit including means which control the starting of the synchronously-operating mechanism from a predetermined position. 75
59. In a wireless-telegraph system comprising synchronously-operating mechanism at each station, a key controlling the transmitter-circuit and also controlling a circuit including means which control the locking of the synchronously-operating mechanism in a definite position. 80
60. In a wireless-telegraph system comprising synchronously-operating mechanism at each station, a key controlling the transmitter-circuit and also controlling a circuit including means which control the starting of the synchronously-operating mechanism from and locking it in a predetermined position. 85
61. In a wireless-telegraph system comprising synchronously-operating mechanism at each station, a key controlling the transmitter-circuit and also controlling a circuit including means which control the locking of the synchronously-operating mechanism a definite interval of time after the last operation of said key. 90
62. In a wireless-telegraph system comprising synchronously-operating mechanism at each station, a key controlling the transmitter-circuit and simultaneously controlling a circuit including means which control the operation of the synchronously-operating mechanism. 95
63. In a wireless-telegraph system comprising synchronously-operating mechanism at each station, a key controlling the transmitter-circuit and simultaneously controlling a circuit including means which control the starting of the synchronously-operating mechanism. 100
64. In a wireless-telegraph system comprising synchronously-operating mechanism at each station, a key controlling the transmitter-circuit and simultaneously controlling a circuit including means which control the locking of the synchronously-operating mechanism. 105
65. In a wireless-telegraph system comprising synchronously-operating mechanism at each station, a key controlling the transmitter-circuit and simultaneously controlling a circuit including means which control the starting and locking of the synchronously-operating mechanism. 110
66. In a wireless-telegraph system comprising synchronously-operating mechanism at each station, a key controlling the transmitter-circuit and simultaneously controlling a circuit including means which control the locking of the synchronously-operating mechanism. 115

cuit including means which control the starting of the synchronously-operating mechanism from a predetermined position.

67. In a wireless-telegraph system comprising synchronously-operating mechanism at each station, a key controlling the transmitter-circuit and simultaneously controlling a circuit including means which control the locking of the synchronously-operating mechanism in a definite position.

13. **15** is in a desired position.

68. In a wireless-telegraph system comprising synchronously-operating mechanism at each station, a key controlling the transmitter-circuit and simultaneously controlling a circuit including means which control the starting of the synchronously-operating mechanism from and locking it in a predetermined position.

69. In a wireless-telegraph system comprising synchronously-operating mechanism at each station, a key controlling the transmitter-circuit and simultaneously controlling a circuit including means which control the locking of the synchronously-operating mechanism a definite interval of time after the last operation of the key.

70. In a wireless-telegraph system comprising synchronously-operating mechanism at each station, a key controlling the transmitter-circuit and simultaneously controlling a circuit including means which control the starting of the synchronously-operating mechanism from a predetermined angular position

71. In a wireless-telegraph system comprising synchronously-operating mechanism at each station, a key controlling the transmitter circuit and simultaneously controlling a circuit including means which control the locking of the synchronously-operating mechanism in a definite angular position.

48 ISM in a definite angular position.

72. In a wireless-telegraph system comprising synchronously-operating mechanism at each station, a key controlling the transmitter-circuit and simultaneously controlling a circuit including means which control the starting of the synchronously-operating mechanism from and locking it in a predetermined angular position.

45

73. In a multiplex wireless-telegraph system comprising synchronously-operating mechanism at each station, a plurality of keys controlling the transmitter-circuits and also controlling circuits including means which control the operation of the synchronously-operating mechanism.

74. In a multiplex wireless-telegraph system comprising synchronously-operating mechanism at each station, a plurality of keys controlling the transmitter-circuits and also controlling circuits including means which control the starting of the synchronously-operating mechanism.

75. In a multiplex wireless-telegraph sys-

75. In a multiplex wireless-telegraph system comprising synchronously - operating mechanism at each station, a plurality of keys 65 controlling the transmitter-circuits and also controlling circuits including means which

control the locking of the synchronously-operating mechanism.

76. In a multiplex wireless-telegraph system comprising synchronously-operating mechanism at each station, a plurality of keys controlling the transmitter-circuits and also controlling circuits including means which control the starting and locking of the synchronously-operating mechanism. 75.

77. In a multiplex wireless-telegraph system comprising synchronously-operating mechanism at each station, a plurality of keys controlling the transmitter-circuits and also controlling circuits including means which control the starting of the synchronously-operating mechanism from a predetermined position. 80

78. In a multiplex wireless-telegraph system comprising synchronously-operating mechanism at each station, a plurality of keys controlling the transmitter-circuits and also controlling circuits including means which control the locking of the synchronously-operating mechanism in a definite position. 85 90

79. In a multiplex wireless-telegraph system comprising synchronously-operating mechanism at each station, a plurality of keys controlling the transmitter-circuits and also 95 controlling circuits including means which control the starting of the synchronously-operating mechanism from and locking it in a predetermined position.

80. In a multiplex wireless-telegraph system comprising synchronously-operating mechanism at each station, a plurality of keys controlling the transmitter-circuits and also controlling circuits including means which control the locking of the synchronously-operating mechanism a definite interval of time after the last operation of any one of said keys. 105

81. In a multiplex wireless-telegraph system comprising synchronously-operating mechanism at each station, a plurality of keys alternately controlling the transmitter-circuits and also alternately controlling circuits including means which control the operation of the synchronously-operating mechanism. 110

82. In a multiplex wireless-telegraph system comprising synchronously-operating mechanism at each station, a plurality of keys alternately controlling the transmitter-circuits and also alternately controlling circuits including means which control the starting of the synchronously-operating mechanism. 115
120

83. In a multiplex wireless - telegraph system comprising synchronously - operating mechanism at each station, a plurality of keys alternately controlling the transmitter - circuits and also alternately controlling circuits including means which control the locking of the synchronously-operating mechanism. 125

84. In a multiplex wireless-telegraph system comprising synchronously-operating mechanism at each station, a plurality of keys alternately controlling the transmitter-circuits and also alternately controlling circuits including means which control the starting 130

and locking of the synchronously-operating mechanism.

85. In a multiplex wireless-telegraph system comprising synchronously-operating mechanism at each station, a plurality of keys alternately controlling the transmitter-circuits and also alternately controlling circuits including means which control the starting of the synchronously-operating mechanism from a predetermined position.

86. In a multiplex wireless-telegraph system comprising synchronously-operating mechanism at each station, a plurality of keys alternately controlling the transmitter-circuits and also alternately controlling circuits including means which control the locking of the synchronously-operating mechanism in a definite position.

87. In a multiplex wireless-telegraph system comprising synchronously-operating mechanism at each station, a plurality of keys alternately controlling the transmitter-circuits and also alternately controlling circuits including means which control the starting of the synchronously-operating mechanism from and locking it in a predetermined position.

88. In a multiplex wireless-telegraph system comprising synchronously - operating mechanism at each station, a plurality of keys alternately controlling the transmitter-circuits and also alternately controlling circuits including means which control the locking of the synchronously - operating mechanism a definite interval of time after the last operation of any one of said keys.

89. In a multiplex wireless-telegraph system comprising synchronously - operating mechanism at each station, a plurality of keys
40 controlling transmitter-circuits and simultaneously controlling circuits including means which control the operation of the synchronously-operating mechanism.

45 90. In a multiplex wireless-telegraph system comprising synchronously-operating mechanism at each station, a plurality of keys controlling transmitter-circuits and simultaneously controlling circuits including means which control the starting of the synchronously-operating mechanism.

91. In a multiplex wireless-telegraph system comprising synchronously-operating mechanism at each station, a plurality of keys controlling transmitter-circuits and simultaneously controlling circuits including means which control the locking of the synchronously-operating mechanism.

92. In a multiplex wireless-telegraph system comprising synchronously-operating mechanism at each station, a plurality of keys controlling transmitter-circuits and simultaneously controlling circuits including means which control the starting and locking of the synchronously-operating mechanism.

65 93. In a multiplex wireless-telegraph system comprising synchronously-operating mechanism at each station, a plurality of keys

controlling transmitter-circuits and simultaneously controlling circuits including means which control the starting of the synchronously-operating mechanism from a predetermined position.

94. In a multiplex wireless-telegraph system comprising synchronously-operating mechanism at each station, a plurality of keys 75 controlling transmitter-circuits and simultaneously controlling circuits including means which control the locking of the synchronously-operating mechanism in a definite position. 80

95. In a multiplex wireless-telegraph system comprising synchronously-operating mechanism at each station, a plurality of keys controlling transmitter-circuits and simultaneously controlling circuits including means which control the starting of the synchronously-operating mechanism from and locking it in a predetermined position. 85

96. In a multiplex wireless-telegraph system comprising synchronously - operating mechanism at each station, a plurality of keys controlling transmitter-circuits and simultaneously controlling circuits including means which control the locking of the synchronously-operating mechanism a definite interval of time after the last operation of any one of said keys. 90 95

97: In a multiplex wireless-telegraph system comprising synchronously-operating mechanism at each station, a plurality of keys alternately controlling transmitter-circuits and simultaneously controlling circuits including means which control the operation of the synchronously-operating mechanism. 100

98. In a multiplex wireless-telegraph system - comprising synchronously - operating mechanism at each station, a plurality of keys alternately controlling transmitter - circuits and simultaneously controlling circuits including means which control the starting of the synchronously-operating mechanism. 105 110

99. In a multiplex wireless-telegraph system comprising synchronously-operating mechanism at each station, a plurality of keys alternately controlling transmitter-circuits and simultaneously controlling circuits including means which control the locking of the synchronously-operating mechanism. 115

100. In a multiplex wireless-telegraph system comprising synchronously - operating mechanism at each station, a plurality of keys alternately controlling transmitter-circuits and simultaneously controlling circuits including means which control the starting and locking of the synchronously-operating mechanism. 120 125

101. In a multiplex wireless-telegraph system comprising synchronously-operating mechanism at each station, a plurality of keys alternately controlling transmitter-circuits and simultaneously controlling circuits including means which control the starting of the synchronously-operating mechanism from a predetermined position. 130

102. In a multiplex wireless-telegraph system comprising synchronously - operating mechanism at each station, a plurality of keys alternately controlling transmitter-circuits and simultaneously controlling circuits including means which control the locking of the synchronously-operating mechanism in a definite position.

103. In a multiplex wireless-telegraph system comprising synchronously - operating mechanism at each station, a plurality of keys alternately controlling transmitter-circuits and simultaneously controlling circuits including means which control the starting of the synchronously-operating mechanism from and locking it in a predetermined position.

104. In a multiplex wireless-telegraph system comprising synchronously - operating mechanism at each station, a plurality of keys alternately controlling transmitter-circuits and simultaneously controlling circuits including means which control the locking of the synchronously-operating mechanism a definite interval of time after the operation of any one of said keys.

105. In a wireless-telegraph system, synchronously-moving transmitting and receiving commutators at each of a plurality of stations and means controlled by a transmitter of electromagnetic waves and by an electro-

magnetic wave-responsive device for starting the commutators.

106. In a wireless-telegraph system, synchronously-moving transmitting and receiving commutators at each of a plurality of stations and means controlled by a transmitter of electromagnetic waves and by an electromagnetic wave-responsive device for starting the commutators from rest.

107. In a wireless-telegraph system, synchronously-moving transmitting and receiving commutators at each of a plurality of stations and means controlled by a transmitter of electromagnetic waves and by an electromagnetic wave-responsive device for starting the commutators from rest in a definite angular position.

108. In a multiplex wireless-telegraph system, synchronously-moving transmitting and receiving commutators, a plurality of transmitters of electromagnetic waves and a plurality of electromagnetic wave-responsive devices associated therewith, and means for stopping the commutators in a definite position a definite interval of time after the last transmitted or received impulse.
